United States Patent Office

Des. 223,285
Patented Apr. 4, 1972

223,285

CIGARETTE LIGHTER

Sadao Yoshinaga, Tokyo, Japan, assignor to Yoshinaga
Prince Co., Ltd., Tokyo, Japan

Filed Mar. 10, 1971, Ser. No. 123,123

Claims priority, application Japan Sept. 22, 1970

Term of patent 14 years

Int. Cl. D27—05

U.S. Cl. D47—27

Fig.2

Fig.1

Fig.3

Fig.4

Fig.6

Fig.5

FIG. 1 is a front elevational view of a cigarette lighter showing my new design;

FIG. 2 is a side elevational view taken from the left of FIG. 1;

FIG. 3 is a side elevational view taken from the right of FIG. 1;

FIG. 4 is a top view thereof;

FIG. 5 is a bottom view thereof; and

FIG. 6 is a perspective view thereof.

The switch is shaded in FIGS. 1 and 6 to indicate contrast.

I claim:

The ornamental design for a cigarette lighter, as shown and described.
